CONVECTION-COMPENSATING
CENTRIFUGE

Charles F. Hall, Berkeley, Calif.

Application July 22, 1946, Serial No. 685,393

2 Claims. (Cl. 233—1)

1

My invention relates to a continuous flow, cross current, "Convection-Compensating Centrifuge," in which separation of fluid constituents of different mass is accomplished by means of adjacent oppositely flowing component axial currents having component cross currents which flow predominantly centrifugal across one axial current and predominantly centripetal across the opposite axial current; thus providing a high resolving power free of remixing defects. It shows alternative and supplementary methods and improvements relating to my copending patent applications Serial No. 583,381, filed March 17, 1945, now abandoned; Serial No. 624,761, filed October 26, 1945, now abandoned; Serial No. 654,753, filed March 15, 1946, now abandoned; and Patent No. 2,546,186, issued March 27, 1951. Its main feature is a rotor comprising heat insulative and heat conductive partition segments in combination with a central cooling system, to provide necessary temperature gradients within the rotor.

Throughout the specification and claims the term "axial" or "axially" is used to denote a direction parallel or componently parallel to the axis of the centrifuge rotor; thus the expression "axially inclined perforations" designates perforations that are inclined to provide a component of fluid flow in a direction that is parallel to the axis; and the term "axial separation" designates a separation or enrichment of separable constituents that takes place in a direction that is parallel to the axis. The term "centripetal" is used to denote a direction radially inward toward the axis of the rotor. The term "centrifugal" is used to denote a direction radially outward from the axis of the rotor. And the term "circumferential" is used to denote a direction extending through the cord of an arc concentric to the circumference of the rotor. The word "radially" is used in its broadest sense to denote radii extending as components of centrifugal force. The term "centripetal cross current" is used to denote a radially inward component of current that crosses a component of axial current. The term "centrifugal cross current" is used to denote a radially outward component of current that crosses a component axial current. The term "axial current" is used to denote component axial current.

In the accompanying drawings: Fig. 1 is a horizontal longitudinal section of the device, sectioned on the line 1—1, Fig. 3 and Fig. 4. Fig. 2 is a reflected view of a section on the line 2—2, Fig. 1. Fig. 3 is a reflected view of a segment sectioned on the line 3—3, Fig. 1. Fig. 4 is a reflected view of a segment sectioned on the line

4—4, Fig. 1. Fig. 5 is an end view and Fig. 6 is an elevation of one of the heat insulative baffle segments. Fig. 7 is a reflected end view of one flue as sectioned on the line 4—4, Fig. 1; it shows arrows to indicate the flow of fluid around a baffle segment, especially showing centrifugal and centripetal cross currents. Fig. 8 is a section through a flue on the line 8—8, Fig. 7, and a section through a baffle segment on the line 8, Fig. 5; it shows arrows to indicate the flow of fluid around a baffle segment, especially showing axial currents. Fig. 9 is a section on the line 9—9, Fig. 5; it is a view of a broken part of a mid-length of a baffle segment showing a section of axially inclined perforations. Similar numerals refer to similar parts throughout the drawings.

The tubular stationary axle 1 is divided into three internal channels by the three sided partition 2. It is attached to the beam 3, to the stationary disk 4, to the smooth surfaced sleeve gaskets 5 and 6, and to the radial extension tubes 7.

The long cylindrical outer wall 8, of the rotor, is attached to the end disk and hub member 9 attached to the drive gear 10 and carrying the bearings 11. It is also attached to the end disk and hub member 12 carrying the bearings 13 and attached to the inner cylindrical wall 14 hermetically sealed to the inner disk caps 15 and 16 attached to the inner hub members 11 and 13. The annular channels 19 and 20 are filled with oil or mercury which provides centrifugal liquid seals around each annular flange of each of the two sleeve gaskets 5 and 6. The annular space, between the cylindrical walls 8 and 14, is partitioned into axial flues 48 by the heat insulative baffle segments 21, by the heat conductive segments 22 conductive to the wall 8, and by the heat conductive segments 23 conductive to the wall 14.

Each flue 48 is circumferentially divided by a radially and axially extending baffle segment 21. Near the radially outer part of each baffle segment are the axially inclined perforations 29 and near the radially inner part of each baffle segment are the axially inclined perforations 30. The perforations 29 and 30 have the same axial inclination for any given baffle segment within a flue, but for the parallel connection of flues shown, the axial inclination of the perforations is reversed in every alternate flue, so that they have the same inclination facing towards opposite sides of their common heat conductive segment 22, see Fig. 9.

For a device of larger diameter additional concentric rings of flues may be provided to increase

the magnitude of separation; it is best to make the radial dimension of the flues as small as possible.

The diffusion plugs 28 may each be made of tightly packed fiber glass cloth cemented in a peripheral plastic sleeve 50 cemented in the ends of the flues as shown. They should be made so that their length and open area limits diffusion in a flue to approximately that of the volume of fluid being separated through the flue; thus practically eliminating defects of irregular convection currents between the parallel connected flues.

The tubular stationary axle 31 is divided into two internal channels by the partition 32. It is attached to the beam 33 and to the stationary central cooling system 34 carrying the bearings 35 supported on the rotary inner hub 17. A cold liquid is circulated through the internal channels of the axle 31 and through the longitudinal coils 36 of the central cooling system. By means of convection and radiation the center of the rotor is thus cooled, and since the heat conductive segments 23 make better thermal contact, with the center wall 14 of the rotor, they are more quickly and effectively cooled than are the segments 21 and 22, and so a circumferential temperature gradient is established across each flue between each segment 22 and 23. This circumferential temperature gradient across each flue is augmented by convectional displacement of cool fluid from the radially inner wall and warm fluid from the radially outer wall of each flue.

Supported on the beams and enclosing the rotor is the stationary, electrically heated housing 37 which is divided into the end length compartments covered with the electric heating units 38 and 39, and the mid-length compartment covered with the electric heating unit 40. The rings 41 and 42 serve to restrict convectional transfer of heat between compartments of the housing 37. So that heat from the unit 40 goes directly to the mid-length of the rotor, and heat from the units 38 and 39 goes directly to the respective end-lengths of the rotor. The mid-length heating unit 40 is electrically connected through the diagrammatically shown electrical connections 49 and in operation it may be maintained at a higher temperature than the end-length heating units 38 and 39 which are electrically connected through the diagrammatically shown electrical connections 54 and 55, respectively. Axial temperature gradients, produced by heat conducted from the bearings, are thus roughly neutralized throughout the rotor.

Fluid, having molecular, colloidal or other constituents to be separated, is fed through the Y-connection tube 44 into the channels 51 connecting to an extension tube 7 which connects to the inlet chamber 43. As shown in Fig. 3, this extension tube 7 is curved in the direction of rotation so that rotation of the fluid in the chamber 43 sucks fluid through the tube. The diametrically opposite extension tube 7, Fig. 1, is curved in the opposite direction to rotation so that the rotating fluid is compressed into its end and is forced through the channel 52. The channels 51 and 52 are connected together, through an inlet chamber of a second centrifuge not shown, and thus fluid is continuously circulating and mixing through these channels.

From the inlet chamber 43 the fluid and its constituents passes through the diffusion plugs 28 and into the flues 48.

Considering the flow of fluid in one flue 48,

as shown by the arrows in Figs. 1, 7, and 8: the heat conductive segment 22 is heated by its contact to the periphery of the rotor and thereby warms fluid on one side of the baffle segment 21; and the heat conductive segment 23 is cooled by its contact to the center of the rotor and thereby cools fluid on the opposite side of the baffle segment. This circumferentially unbalances the centrifugal head of pressure so that fluid passes from the cooled side of the flue to the heated side through the axially inclined perforations 29 along the radially outer part of the baffle segment and it passes from the heated side to the cooled side through the axially inclined perforations 30 along the radially inner part of the baffle segment. In passing through the axially inclined perforations it is given an axial circulation; thus as seen in Fig. 8, there is a downward cooled axial current on the cooled side and an upward heated axial current on the heated side; and as seen in Fig. 7, there is a centrifugal cross current on the same side as the downward cooled axial current and a centripetal cross current on the same side as the upward heated axial current. Within the fluid are both heavy and light weight separable constituents which are affected by centrifugal force and for the illustration given herein it is considered that the heavier constituents have faster centrifugal sedimentation velocities than the lighter constituents. For separation of constituents such as molecules or colloidal particles the velocity of the cross currents is greater than the centrifugal sedimentation velocities of the constituents; and so the cross currents carry the constituents around the baffle segment. Due to the differences in centrifugal sedimentation velocities, the lighter constituents, as carried in the centrifugal cross current, travels slower than the heavier constituents and thus the lighter constituents are enriched within the cooled axial current and are displaced and axially enriched in the direction of said cooled axial current. But in the centripetal cross current the heavier constituents travel slower than the lighter constituents and thus the heavier constituents are enriched within the heated axial current and are displaced and axially enriched in the direction of said heated axial current. The axial enrichment is dependent upon averaged differences in the summation of the centrifugal and centripetal cross currents and sedimentation velocities as circumferentially maintained by the baffle segment. It is not dependent upon maintaining a state of centrifugal enrichment and so it is not adversely affected by centrifugal and centripetal circulation of the fluid which destroys or defects the centrifugal enrichment necessary in other types of centrifuges.

For a full length rotor the mid-length of a flue may be three or four feet long so the total aggregate open area of the perforations extending along a baffle segment is large to provide a large volume of cross current circulation. To shorten end affects and complete circulation there are diagonally opposite openings 46 and 47 at the ends of each baffle segment.

For the example given herein, the cooled axial current is directed toward the inlet chamber 43 and so the enrichment of lighter constituents, from each flue 48, diffuses through the diffusion plugs 28 into the chamber 43 where it mixes with the continuously circulating fluid in the inlet channels. The heated axial current is directed toward the annular outlet chamber 25 and so the enrichment of heavier constituents, from

each flue 48, diffuses through the diffusion plugs 28 into the chamber 25. In one of the flues, shown at the right of Fig. 1, the baffle segment 21 and diffusion plugs 28 are omitted and a cap 24 closes one end of the flue. This flue is in open communication at one end with the annular outlet chamber 25 and at the other end communicates through hole 27 with outlet 26 in open communication with the channel 53, Fig. 2, which connects to the outlet duct 45 through which the enrichment of heavier constituents may be drawn off.

Instead of being extended axially, the flues may be extended circumferentially or in any desired direction which is componently transverse to the direction of the centrifugal field.

I claim:

1. In a centrifuge a cylindrical rotor, a central cooling system axially extending through the center of the rotor, end-length and mid-length heating units peripherally surrounding the rotor, said rotor having a plurality of flues axially extending therethrough for the circulation of fluid carrying separable constituents, a baffle segment circumferentially dividing each flue, each baffle segment having a multiplicity of closely spaced axially inclined perforations passing through a radially outer part of the baffle segment and a corresponding multiplicity of closely spaced axially inclined perforations passing through a radially inner part of the baffle segment, in each flue and on one side of the baffle segment within the flue a heat conductive segment in thermal contact with the radially outer heated wall of the rotor and thermally insulated from the radially inner cooled wall of the rotor and on the opposite side of the baffle segment within the flue a heat conductive segment in thermal contact with the radially inner cooled wall of the rotor and thermally insulated from the radially outer heated wall of the rotor, said heat conductive segments providing circumferential temperature gradients across each flue thereby producing convectional circulation of fluid through the axially inclined perforations and said perforations being so positioned that the circulation produces oppositely directed component axial currents on circumferentially opposite sides of each baffle segment and produces component cross currents which flow predominantly centrifugal across one component axial current and flow predominantly centripetal across the oppositely directed component axial current, at opposite ends of the rotor

annular inlet and outlet chambers connecting the ends of the flues to inlet and outlet ducts, connected to the ducts within the chambers stationary extension tubes to circulate the fluid through the ducts and thereby discharge an enrichment of constituents as enriched by the circulation of fluid within the flues.

2. In a centrifuge a cylindrical rotor, a central cooling system axially extending through the center of the rotor providing radial temperature gradients throughout the rotor, axially extending through the rotor a number of flues circumferentially divided by perforated baffle segments through which fluid and separable constituents circulate, circumferentially on one side of each flue a heat conductive segment in thermal contact with the radially outer heated wall of the rotor and thermally insulated from the radially inner cooled wall of the rotor and on the circumferentially opposite side of the flue a heat conductive segment in thermal contact with the radially inner cooled wall of the rotor and thermally insulated from the radially outer heated wall of the rotor, said heat conductive segments providing circumferential temperature gradients across each flue the said perforations being so positioned that the temperature gradients produce convectional circulation of fluid and enrichment of constituents within the flues.
